DESIGN FOR A SET OF GAME PIECES

Samuel Eppy, Jamaica, N. Y.

Application July 8, 1943, Serial No. 110,625

Term of patent 3½ years

To all whom it may concern:

Be it known that I, Samuel Eppy, a citizen of the United States and a resident of Jamaica, in the county of Queens, city and State of New York, with a post office address at No. 333 Hudson Street, in the Borough of Manhattan, county, city, and State of New York, have invented a new, original, and ornamental Design for a Set of Game Pieces, of which the following is a specification, reference being had to the accompanying drawing, forming part thereof, in which the drawings are plan views of a set of game pieces showing my new design.

The game pieces are substantially the thickness of playing cards.

I claim:

The ornamental design for a set of game pieces, as shown and described.

SAMUEL EPPY.
